BOAT FOR TRANSPORTING AUTOMOBILES

Robert H. Robertson, 2640 Heatherwood,
Dallas, Tex. 75228

Filed Aug. 11, 1966, Ser. No. 3,437

Term of patent 14 years

(Cl. D71—1)

FIG. 1

FIG. 2

FIG. 3

FIG. 4

FIGURE 1 is a perspective view of a boat for transporting automobiles showing my new design as it appears when the boat is viewed from above and forward of the boat.

FIGURE 2 is a perspective view of the lower side of the boat.

FIGURE 3 is an elevational view of the boat as it appears when viewed from directly ahead, or forward of, the boat.

FIGURE 4 is an elevational view of the boat as it appears when viewed from directly behind, or astern of, the boat.

FIGURE 5 is a side elevational view of the boat showing my new design.

FIGURE 6 is a bottom view of the boat showing my new design.

The broken line disclosure is for illustrative purposes only.

I claim:

The ornamental design for a boat for transporting automobiles, substantially as shown and described.
